Patented June 4, 1918.

UNITED STATES PATENT OFFICE

EBER B. WHITE, OF SOUTH BEND, INDIANA.

VALVE-GRINDING TOOL.

1,268,309.

Specification of Letters Patent. Patented June 4, 1918.

Application filed July 26, 1916, Serial No. 111,510.

To all whom it may concern:

Be it known that I, EBER B. WHITE, a citizen of the United States, residing at South Bend, in the county of Saint Joseph and State of Indiana, have invented certain new and useful Improvements in Valve-Grinding Tools, of which the following is a specification.

This invention relates to a valve grinding tool and more particularly to an improved implement for imparting a reciprocatory motion to the disks in puppet valves whereby they may be ground after becoming worn from constant use.

15 The primary object of the invention is to provide an implement adapted to be attached to the valve disk whereby the disk may be rotated in its seat for grinding both the seat and the disk.

20 A further object of the invention is to provide a device of this character that may be used in connection with various types of valve disks, the valve engaging members of the implement being adapted to receive 25 either a slotted disk or the disk of the type usually provided with oppositely disposed recesses on their top surfaces.

25 A further object of this invention is the provision of a valve grinding tool which consists of comparatively few parts and is simple in construction, but durable and well adapted to withstand the rough usage to which devices of this character are ordinarily subjected.

35 For a full description of the invention and the advantages and merits thereof, reference is to be had to the following description and the accompanying drawings, wherein is illustrated the preferred form of my invention, in which;

Figure 1 is a side elevation.

Fig. 2 is a transverse section on the line 2—2 of Fig. 1.

Fig. 3 is a fragmentary side elevation 45 showing the wedge-shaped valve engaging member removed and the auxiliary valve engaging member secured to the end of the operating shaft.

Fig. 4 is a vertical section through the auxiliary valve engaging member.

Fig. 5 is a section on the line 5—5 of Fig. 4.

Fig. 6 is a detail perspective view of one of the valve engaging members used with the 55 device.

The operating shaft 1 consists of a flat

strip of metal twisted to provide the spiral groove which receives the operating sleeve 2. The operating sleeve 2 serves as a handle for operating the device and is of substantially 60 cylindrical formation having a central cylindrical bore through which the operating shaft 1 passes. The sleeve 2 carries a pair of spaced apart bolts 3 between which the operating shaft 1 is extended so that a reciprocatory motion is imparted to the operating shaft 1 when the sleeve 2 is moved upwardly and downwardly on the operating shaft. The upper end of the operating shaft carries a hand grip 4 which is rotatably 65 mounted on the end of the operating shaft so that the shaft may be rotated when the hand grip 4 is held stationary.

It is well known that various types of valve disks are provided with slots or recesses for receiving a tool whereby the valve may be ground. In order that this improved implement may be as universal as possible I provide a structure whereby the implement may be employed in connection 80 with both slotted valve disk and with the disks provided with depressions or circular recesses. The lower end of the operating shaft 1 carries a valve member 5 which is constructed similar to the ordinary screwdriver, the end being wedge-shaped whereby it may be inserted in the slot in the top of a valve disk. This valve engaging member 5 is adapted to receive the end of the operating shaft 1 and is removably secured thereto 90 by means of a set screw 6.

An auxiliary valve engaging member 7 is provided for use in connection with the types of valves which are provided with the oppositely disposed circular recesses. This valve 95 engaging member 7 is carried, when not in use, by the shaft 1 and is held in inoperative position by the upper end of the member 5. When it is desired to use the member 7, the set screw 6 will be removed thereby detaching the member 5 from the end of the shaft 1 and the member 7 may be moved to the end of the shaft 1 until the aperture 8 is in alignment with the screw receiving opening in the end of the shaft whereupon the set screw 105 may be employed for fastening the member 7 in engagement with the operating shaft 1. It will be noted from a consideration of Fig. 6 of the drawing that the removable member 5 is provided with a slot for detachably connecting the member to the end of the spiral shaft 1 whereby the member 7 may be moved

down to the end of the shaft for permitting the said screw to be inserted through the opening 8 for fastening the member 7 to the end of the shaft.

5 The auxiliary valve engaging member 7 consists of a casing of substantially rectangular formation as clearly shown by Figs. 4 and 5 of the drawing and is open at each end. The top wall 9 of the casing is provided with a slot 10 through which the operating shaft 1 is extended and the lower wall 11 is provided with a slot 12 which is longer than the slot 10 and is adapted to receive the studs 13 which are adapted to be 10 extended into the depressions or circular recesses in the top of the valve whereby the valve may be rotated. The upper ends which extend in the interior of the casing, are provided with screw threads for receiving the nuts 14 which are disposed within the casing and the studs are also provided with nuts 15 disposed on the exterior of the casing and bearing against the bottom wall 11 thereof. The screw threads together with 15 the nuts 14 and 15 permit an adjustment of the studs 13 when it is desired to adjust the length of the stud. It will be observed that the slot 12 permits the studs 13 to be moved closer together if the holes in the valve are 20 close together.

From the foregoing it will be observed that a very simple and durable valve grinding tool has been provided, the details of which embody the preferred form. I de-

sire it to be understood however, that slight changes in the minor details of construction may be made without departing from the spirit of the invention in the scope of the claim hereunto appended.

40

I claim:

The valve grinding tool comprising a spiral shaft having an operating sleeve mounted thereon for turning the said shaft, a hollow casing mounted on the lower ends of the shaft and including a substantially rectangular member having both ends open the bottom wall of the casing being provided with a longitudinal slot having the lower end of the said shaft extended therethrough, the upper wall of the casing also having a slot of relatively less length than the lower slot, studs mounted in the ends of the said lower slot, the interior of said casing being provided with a pair of nuts of a width equal to the width of the said casing whereby the said nuts will be prevented from turning, the said studs having screw threaded ends adapted to be received in the said nuts, the said elongated slot in the lower portion of the casing permitting longitudinal adjustment of the studs toward and away from each other.

45

In testimony whereof I affix my signature in presence of two witnesses.

EBER B. WHITE.
